UNITED STATES PATENT OFFICE.

DAVID HINDAHL, OF CHICAGO, ILLINOIS, ASSIGNEE TO HARRY S. HART, OF CHICAGO,
ILLINOIS.

DOOR STOP.

Application filed August 6, 1921. Serial No. 490,370.

To all whom it may concern:

Be it known that I, DAVID HINDAHL, a citizen of the United States, residing at Chicago, in the county of Cook and State of Illinois, have invented certain new and useful Improvements in Door Stops, of which the following is a specification.

This invention relates to a new and improved door stop for railway cars, and more particularly to a device adapted to limit the movement of laterally swinging doors upon dump cars.

A number of types of dump cars as now constructed are provided with laterally swinging doors either simply over the trucks or throughout the full length of the car. These doors are positively latched or locked shut when the car is loaded. The doors generally swing free, however, when they are unlatched, and men working with the cars very generally neglect to latch the doors after emptying the cars. When the cars are handled with the doors unlatched, the doors tend to swing outwardly, due to centrifugal force on curves or due to jolting, and may swing considerably beyond the side of the car. Such doors swinging outwardly may cause injury to persons standing adjacent the track and may injure the doors or objects near the right of way.

It is an object of the present invention to provide means associated with the doors adapted to limit the swinging movement of the doors and normally to prevent swinging movement beyond a predetermined intermediate point in their range of movement.

It is a further object to provide such means so constructed as to be readily operable to permit further movement of the door to afford the full discharge opening.

It is an additional object to so construct the means that it may serve as a prop to maintain the door in its fully opened position.

Other and further objects will appear as the description proceeds.

The embodiment of my invention selected for purposes of illustration, comprises a link connected to a fixed part of the car, the link being slotted and carrying a floating pin.

A slotted member is attached to the door, the floating pin carried by the link also coacting with this latter slotted member. The slot in the member upon the door is formed

55 with a lower angular portion which is sub-

stantially tangential to the arc of movement of the floating pin, as limited by the slot in the link. The location of this portion and the length of the slot in the link are such that when the floating pin is in this portion 60 of the slot and at the end of the slot in the link, the door is substantially in the plane of the side of the car. In this position the pin serves to prevent further outward movement of the door. Upward movement imparted to the pin or link causes the pin to move out of the angular portion into an extension of the slot in the member upon the door, thus permitting the door to swing to its fully opened position. A lug is formed 70 upon the slotted door member adapted to engage the end of the link to maintain the door in open position.

I have illustrated a preferred embodiment of my invention in the accompanying drawings, in which—

Figure 1 is a cross section of the car equipped with my door check, the section being taken on line 1—1 of Figure 2; and

Figure 2 is a fragmentary side elevation 80 of a car showing the laterally swinging door equipped with my check.

Referring to the drawings, the car comprises the end 3, sides 4, center sills 5, bolster 6, and hopper bottom 7. The end of the car over the trucks is formed with the laterally inclined floor portions 8, adapted to discharge material either side of the track through openings closed by doors 9. These doors 9 are hingedly connected at 10 to the car sides 85 and are each provided with a latch 11. The links 12 are pivotally connected to the fixed portion of the car at 13. The lower portions of the links are provided with the slots 14 in which are carried the floating pins 15. 90 These pins also fit in the slots 16 formed in members 17 carried by the door. The lower portions 18 of the slots 16 are angularly disposed relative to the major portion of the slots. The upper portions of the members 17 are provided with lugs 19 for coacting with the links to maintain the doors open. 95

The door is shown closed at the left of Figure 1. In this position the pin 15 is in the angular portion 18 of the slot 16, and it is at the upper end of the slot 14 in the link 12. If the door is unlatched it will be swung by gravity to the substantially vertically position shown in full lines at the right of Figure 1. The pin 15 remains in the same 110

relation to the slot 16, but has passed downwardly to the lower end of the slot 14. Due to the angularity of the portion 18 of the slot 16 in which the pin is located, a further 5 outward pull upon the door 9 is positively resisted by the bearing of the pin against the member 17 and the link 14. If, however, the link 14 is positively moved upwardly, so that the pin 15 is carried out of 10 the portion 18 of the slot 16, the door may be swung further outwardly until the pin 15 rides to the upper end of the slot 16. When in this position the lug 19 upon the member 16 engages the end of the link 12 15 and maintains the door in open position. To release the door it is only necessary to move the link 14 downwardly sufficient to clear the lug 19, when the door will be swung by gravity to the position shown in full lines 20 at the right of Figure 1. When in this latter position the link and pin positively prevent the door from swinging outwardly beyond the side of the car, and thus prevent damage due to the swinging door if it 25 should be left unlatched in that position.

While my device has been shown as applied to doors of one particular type of car, it is obviously not limited in its application to cars of that design, but may be applied to 30 swinging doors of any type.

I claim:

1. A railway car having a door adapted to swing to either side of a predetermined 35 normal position, and means for catching and holding the door at its normal position when swinging toward this position from either side.

2. A railway car having a door hinged to hang substantially vertical under the influence of gravity and adapted to swing inwardly toward the car sides and outwardly 40 from the car sides, and means for catching and retaining the door at its substantially vertical position as the door swings toward 45 this position from either side thereof.

3. A railway car having a door normally adapted to hang substantially vertical under the influence of gravity, a slotted member carried by the door and a link connected 50 to the car and to a pin moving in said slot in such manner as to catch and hold the door at its normal position when swinging toward this position from either direction.

4. A railway car having a door normally 55 adapted to hang substantially vertical under the influence of gravity, a slotted member carried by the door and a link connected to the car and to a pin moving in said slot in such manner as to catch and hold the door 60 at its normal position when swinging toward this position from either direction, said link and pin being operable to permit the door to be moved in either direction from normal position.

5. In a railway car having an outwardly

swinging door, a slotted member carried by the door, a link carrying a member associated with said slotted member, in such manner as normally to limit outward movement of the door at less than its full movement. 70

6. In a railway car having an outwardly swinging door, a slotted member carried by the door, a link carrying a member associated with said slotted member in such manner as normally to limit outward movement 75 of the door at less than its full movement, said members being operable to permit full movement.

7. In a railway car having an outwardly 80 swinging door, a slotted link carrying a pin floating in said slot, the link being connected to a fixed portion of the car, and a slotted member carried by the door, the floating pin also fitting in the slot in said member, the slot in said member being so shaped as normally to coact with the floating pin and link to limit movement of the door at less than its full movement.

8. In a railway car having an outwardly 90 swinging door, a slotted link carrying a pin floating in said slot, the link being connected to a fixed portion of the car, and a slotted member carried by the door, the floating pin also fitting in the slot in said member, the 95 slot in said member being so shaped as normally to coact with the floating pin and link to limit movement of the door at less than its full movement, and upon movement of the pin to permit full movement of the door. 100

9. In a railway car having an outwardly swinging door, a slotted link carrying a pin floating in said slot, the link being connected to a fixed portion of the car, and a slotted member carried by the door, the floating pin also fitting in the slot in said member, the slot in said member being so shaped as normally to coact with the floating pin and link to limit movement of the door at less than its full movement, and upon movement 110 of the pin to permit full movement of the door, a portion of said slotted member coacting with the link in the fully open position of the door to maintain the door open.

10. In a railway car having an outwardly 115 swinging door, a slotted link carrying a floating pin in said slot, the link being connected to a fixed portion of the car, and a slotted member carried by the door, the floating pin also fitting in the slot in said member, the slot in said member having an angular portion adapted normally to coact with the pin and link to prevent movement 120 of the door beyond the side plane of the car.

11. In a railway car having an outwardly 125 swinging door, a slotted link carrying a floating pin in said slot, the link being connected to a fixed portion of the car, and a slotted member carried by the door, the floating pin also fitting in the slot in said 130

member, the slot in said member having an angular portion adapted normally to coact with the pin and link to prevent movement of the door beyond the side plane of the car, 5 movement of the pin along said slot beyond the angular portion permitting further movement of the door.

12. In a railway car having an outwardly swinging door, a slotted link carrying a 10 floating pin in said slot, the link being connected to a fixed portion of the car, and a slotted member carried by the door, the floating pin also fitting in the slot in said

member, the slot in said member having an angular portion adapted normally to coact 15 with the pin and link to prevent movement of the door beyond the side plane of the car, movement of the pin along said slot beyond the angular portion permitting further movement of the door, and a lug upon said 20 slotted member adapted to engage the link to maintain the door in open position.

Signed at Chicago, Illinois, this 26th day of July, 1921.

DAVID HINDAHL.
